UNITED STATES PATENT OFFICE.

ROCCO CONFICCHIO, OF MOUNT VERNON, NEW YORK, ASSIGNOR OF TWO-THIRDS TO JOHN KULLMANN AND ALBERT KULLMANN, BOTH OF MOUNT VERNON, NEW YORK.

MEANS FOR ATTACHING RUBBER HEELS TO SHOES.

Application filed July 2, 1926. Serial No. 120,230.

This invention appertains generally to shoes and has more particular reference to new and useful improvements in the manner of attaching rubber heels thereto.

5 An important object of the present invention is the provision of novel and simplified means for securing a rubber heel to the leather heel of a shoe without the use of nails or the like.

10 Another object of the present invention is to provide means whereby the rubber heel may be secured to or detached from the leather heel of a shoe with the expenditure of a minimum amount of time and effort.

15 Another object of the present invention is the provision of novel means of the above character including a fastening plate secured to the leather heel of a shoe and an attaching member carried by the rubber heel and 20 adapted to be detachably engaged with the said fastening plate.

A further object of the present invention is to provide improved means of the above character which are simple yet durable in 25 construction, practical and efficient in use, easy and cheap to manufacture, and well designed for the purposes for which intended.

30 Numerous other objects and advantages of the present invention will become more readily apparent during the course of the following description when taken in connection with the accompanying drawings.

35 In the drawings forming a part of this application and wherein like characters of reference have been employed to designate corresponding parts throughout the several views:

40 Figure 1 is a perspective view of a portion of a shoe showing the fastening plate which is secured to the leather heel thereof.

45 Figure 2 is a perspective view of the improved rubber heel, the said heel being shown in dotted lines while the attaching member carried thereby is shown in full lines.

50 Figure 3 is a side elevation of a portion of a shoe showing the rubber heel secured thereto, said rubber heel and leather heel being shown in section so as to more clearly disclose the manner of attaching the former to the latter.

55 Figure 4 is a sectional view taken on line 4—4 of Figure 3.

Figure 5 is a plan view of the improved rubber heel.

Referring now more in detail to the accompanying drawings wherein for the purpose of illustration has been disclosed a preferred embodiment of the present invention the letter A generally indicates a portion of a shoe which may be of any conventional or preferred make and B the rubber heel arranged to be secured thereto.

The shoe A disclosed herein by way of illustration, embodies in its construction a sole 10 to which is secured, in the usual manner, the upper 11 and the leather heel 12. Carried by the leather heel 12 is a fastening plate generally indicated by the numeral 13 and including a straight portion 14 and the substantially U-shaped portion 15, said attaching plate 13 arranged to be secured to the leather heel 12 in any desired manner such as by means of screws, nails or other fastening elements 16. The straight portion 14 of the attaching plate 13 is provided adjacent its opposite ends with the rearwardly extending struck-up sockets 17 and 18 while the substantially U-shaped portion 15 is provided intermediate its ends with the forwardly directed struck-up socket 19. By reference to Figure 1 of the drawing it will be observed that the sockets 17, 18 and 19 are closed at their sides, the open sides of the sockets 17 and 18 being presented rearwardly and the open side of the socket 19 being presented forwardly, so that when the prongs 28, 29 and 25 are engaged in the sockets 17, 18 and 19, respectively, the anchoring member 20 and consequently the rubber heel, will be held against lateral displacement with respect to the member 13 and the shoe heel A.

The rubber heel B may be of any conventional or preferred type and has molded therein the longitudinally extending attaching member 20 which embodies in its construction a shank 21 and the convergent legs 22 and 23 arranged in substantially V-shaped formation relative to one another. The free end of the shank 21 is bent at right angles as indicated at 24 and is extended through and outwardly of the rubber heel, the terminal thereof being rearwardly directed to provide a prong 25 which is substantially parallel with said rubber heel. The forward ends of the legs 22 and 23 are also bent at right angles as indicated at 26 and 27 and extended through and outwardly of the rubber heel, the terminals thereof being for 100 105 110

wardly directed to provide the prongs 28 and 29 which also extend substantially parallel with the said heel.

When it is desired to secure the rubber heel B to the leather heel 12 of the shoe A, the prong 25 is first inserted into the socket 19 and the rubber heel forced rearwardly as far as possible and transversely flexed. The heel is then permitted to straighten so that 10 the prongs 28 and 29 engage in the sockets 17 and 18. Thus, it will be readily appreciated that the rubber heel will be firmly yet detachably secured to the leather heel 12 of the shoe. When it is desired to remove 15 the rubber heel, it is only necessary to force the same rearwardly and slightly flex the heel until the prongs 28 and 29 are disengaged from the sockets 17 and 18 whereupon the forward end of the heel can be lifted up- 20 wardly and the heel drawn forwardly so as to disengage the prong 25 from the socket 19. It will of course be appreciated that in attaching the rubber heel in place, the prongs 28 and 29 can first be engaged under the lips 25 17 and 18, if desired, and the prong 25 subsequently engaged beneath the lip 19.

It is to be understood that while I have disclosed one practical embodiment of the present invention, changes in the details of 30 construction thereof may be found desirable and the right is hereby reserved to make any such changes as properly fall within the scope of the appended claim without de-

parting from or sacrificing the spirit of the invention.

35

What is claimed is:

Means for securing a rubber heel to the leather heel of a shoe comprising an attaching plate for attachment to the leather heel and embodying a straight forward portion 40 and a substantially U-shaped portion including sides and a connecting bend extending rearwardly from the straight portion, the straight portion being provided, near the juncture of its ends with the said U-shaped 45 portion, with sockets having closed lateral sides and open sides presented rearwardly, the bend of the U-shaped portion being provided with a socket having closed lateral sides and an open side presented forwardly, 50 and an anchoring member comprising a shank and a pair of converging legs united at their meeting ends to the shank at one end thereof, the end portion of the shank and the end portion of each leg being bent 55 substantially at right angles and thence upwardly whereby to provide terminal prongs, the said member being embedded in the said rubber heel except for the said prongs, and the prongs of the legs being engageable in 60 the sockets in the straight portion of the attaching member and the prong upon the shank being engageable in the socket in the bend of the said attaching member.

In testimony whereof I affix my signature.
ROCCO CONTICCHIO.
